UNITED STATES PATENT OFFICE.

JAMES T. ROHM, OF PITTSBURGH, PENNSYLVANIA, ASSIGNOR OF ONE-THIRD TO HERBERT H. ASHMAN, OF PHILIPSBURG, PENNSYLVANIA, AND ONE-THIRD TO JAMES B. SIPE, OF PITTSBURGH, PENNSYLVANIA.

RAIL TIE.

Application filed May 28, 1927. Serial No. 194,902.

This invention relates to a metallic rail tie for use in anchoring and supporting rails in road beds of railways. The general object of the invention is to provide a metallic rail-way tie which is of relatively light construction, which supports the rails by means of resilient supporting members, and in which the rail is electrically insulated from the body of the tie.

One specific object of the invention is to provide a railway tie comprising clamping means so constructed and arranged that the rails may be readily shifted inwardly or outwardly the slight distance necessary to provide the desired variation of gage on curves, and to permit straightening of the track, if the rails have been irregularly laid initially.

Another specific object of the invention is to provide electric insulation between the rail and the clamping portion of the rail tie so arranged that it does not bear the weight of the rail and is not susceptible to wear or abrasion thereby.

Another specific object of the invention is to provide a metallic rail tie in which the clamping members serve to cover the entire open length of a body or trough member, without producing a tie structure of such weight as to render its cost excessive.

In the accompanying drawings Figure 1 is a plan view of the rail tie of the present invention, showing both rails of a track locked in position thereon; Figure 2 is a side elevation of the tie, and corresponds with the showing of Figure 1; Figure 3 is a vertical sectional view through a portion of the tie, showing the attachment of one rail thereto taken on the line 3—3 of Fig. 1; Figure 4 is an end view of the tie and rail; and Figure 5 is a cross sectional view through one of the insulating plates of the structure and the means for attaching it to the rail engaging portion of one of the rail clamping members of the tie.

In the drawings the reference numeral 1 designates a trough shaped metallic tie body, which is desirably rolled from soft open hearth steel and is slightly rounded at the juncture of its sides and base. This body has therein blocks 2 of wood or other suitable resilient material, which project a short distance above the upper edge of the sides of the trough or body member 1. The rails 3

rest upon and are yieldingly supported by these blocks 2.

The tie structure also comprises end clamping members, designated generally by the reference numeral 4, each of which comprises a top plate 5, depending skirts 6 and a rail engaging tongue or extension 7. Each of the skirts 6 of a clamp has therein a slot 8, which match with slots 9 in the sides of the trough or body member 1. A wedge member 10 is adapted to be driven into these slots to the desired extent to secure the clamping member 4 to the trough member 1, and to cause the rail engaging portion 7 of the clamping member to closely engage one side of the rail 3. In order that the wedge 10 may be held in position for close engagement it is provided with a plurality of locking holes 11 for the reception of relatively heavy cotter pins 11^a of copper, brass, or other suitable metal.

The rails are also held in position by means of central clamps, which are designated generally by the reference numeral 12. These clamps each comprise a top plate 13, skirts 14 arranged to depend along the sides of the trough or body member, and rail engaging portions 15. The skirts 14 of the clamps 12 are provided with aligned slots 16 matching with slots 17 in the sides of the trough or body member. A similar wedge 10, provided with locking holes 11 and a cotter pin 11^a serves to lock this clamping member in position on the body of the tie to bear firmly against the inner side of the rail. It will be observed that the positioning of this second wedge is opposite to that of the similar wedge which cooperates with an end clamp 4.

It will be noted that the central clamping members 12 extend a sufficient distance to entirely cover the portion of the trough or body member 1 which lies between the rails, and that they overlap slightly. In order to secure the overlapping effect, one of the central clamps is flared, as indicated at 18, to embrace the end of the other clamp.

Since each of the clamps presses on one side of the rail, and since these clamps are independently secured to the trough member, they provide a ready transverse adjustment of the rail on the tie. In order to make such an adjustment it is necessary merely to

remove the cotter pins 11^a, and to drive out the clamping members 10. The rail may then be shifted to the desired degree, and the clamping members 10 again driven in.

5 It will be noticed that the slots 9 in the sides of the trough or body member 1 are of sufficient width to permit of a material adjustment of the rail on the tie.

Because of the longitudinal extent of the 10 central clamping members 12, the entire length of the trough or body member 1 is covered. This prevents the entrance of moisture, and of other undesired material into the trough member, and also avoids leaving 15 any aperture which might engage the foot of a pedestrian or any object depending beneath the passing train. Because of the overlapping of these central clamps 12 by means of the flare 18 on one of them, they 20 are firmly held in place against springing by the mutual wedging action between them. As all the clamping members may be made of thin gage metal, metal of no more than three-eighths inches thickness being satisfactory, the covering of the trough and the 25 interengagement of the central clamps is obtained without so increasing the weight of the ties as to render them difficult to handle or unduly expensive to manufacture.

30 It is desirable that the tie and the rail be electrically insulated from each other, in order to prevent grounding of any electrical circuit in which the rail is utilized as a conductor. If, as is shown, the rail support 35 consists of a block of wood or other suitable resilient material, this block in itself serves as an insulation. In order to insulate the clamping members from the rail, plates 19 of fibre, rubber composition, or other suitable electrical insulating material, are interposed between the rail engaging portions of the clamp and the rail itself. It is important from the point of view of safety, 40 that these insulating plates be so held that they cannot shift between the clamp and the rail, and that they should be interposed in such position that they are not subject to wear or abrasion, which might loosen the engagement between the clamps and the rail.

45 50 It is also desirable for convenience in shipping and assembling the ties that the insulating plates be directly attached to the rail engaging portions of the clamps. For this reason each of the plates 19 is attached to 55 the rail engaging portion of the clamp with which it is associated by means of one or more plugs 20 of fibre, or other suitable electrical insulating material which is relatively firm and tough. These plugs 20 are held 60 to the insulating plate 19 by means of rivets or the like 21.

In order to completely close the tie structure, end blocks 22, of wood or other suitable material may be inserted, as shown.

65 The rail tie of the present invention pre-

sents the advantages of being strong and light, of being completely closed on its upper surface, of permitting a ready adjustment to permit such slight shifting of the rails as may arise in practice, and provides 70 satisfactory insulation between the rails and the rail tie.

What I claim is:

1. A rail tie comprising a metallic trough member, a rail support of resilient material 75 in said trough and extending above the sides thereof, two metallic rail clamps arranged to be disposed one on each side of a rail and having skirts depending along the sides of the trough member, and oppositely inclined so wedging members, one passing through matching slots in the trough member and one of the clamps and the other passing through matching slots in the trough member and the other of the clamps. 85

2. A rail tie comprising a metallic trough member, a rail support of resilient material in said trough and extending above the sides thereof, a metallic rail clamp having skirts depending along the sides of the trough, 90 means for mutually securing the skirts of the clamping member to the sides of the trough, a rail engaging portion on the clamp, a plate of electrical insulating material between the rail engaging portion of the clamp and the rail, and a plug of relatively firm and tough insulating material interconnecting the plate of insulating material and the rail engaging portion of the clamp. 95

3. A rail tie comprising a metallic trough member, a rail support of resilient material in said trough and extending above the sides thereof, two metallic rail clamps arranged one on each side of a rail and having skirts depending along the sides of the trough member, oppositely inclined wedging members, one passing through matching slots in the trough member and one of the clamps and the other passing through matching slots in the trough member and the other of the clamps, a rail engaging portion on each of the clamps, a plate of electrical insulating material between the rail engaging portion of each clamp and the rail, and a plug of relatively firm and tough insulating material interconnecting the plate of insulating material and the rail engaging portion of the clamp. 110

4. A rail tie comprising a metallic trough member, rail supports of resilient material in said trough and extending above the sides thereof, end rail clamps having skirts depending along the sides of the trough member, means for mutually securing the skirts of said clamps and the sides of the trough, 120 two central rail clamps wholly covering the portion of the trough member lying between the rails, and means for securing said central rail clamps to the trough member. 125

5. A rail tie comprising a metallic trough 130

member, rail supports of resilient material in said trough and extending above the sides thereof, end rail clamps having skirts depending along the sides of the trough member, means for mutually securing the skirts of said clamps and the sides of the trough, two central rail clamps wholly covering the portion of the trough member lying between the rails, said central clamps having a mutual wedging engagement, and means for securing said central clamps to the sides of the trough.

6. A rail tie comprising a metallic trough member, rail supports of resilient material in said trough member and extending above the sides thereof, end rail clamps having skirts depending along the sides of the trough member, means for mutually securing the skirts of said clamps and the sides of the trough, two central rail clamps wholly covering the portion of the trough member lying between the rails, means for securing said central rail clamps to the sides of the trough, a plate of electrical insulating material carried by the rail engaging portion

of each rail clamp, and a plug of relatively firm and tough insulating material attaching each of said plates to the rail engaging portion of a clamp.

7. A rail tie comprising a metallic trough member, rail supports of resilient material in said trough member and extending above the sides thereof, end rail clamps having skirts depending along the sides of the trough member, means for mutually securing the skirts of said clamps and the sides of the trough, two central rail clamps wholly covering the portion of the trough member lying between the rails, said central clamps having a mutual wedging engagement, means for securing said central clamps to the sides of the trough, a plate of electrical insulating material carried by the rail engaging portion of each rail clamp, and a plug of relatively firm and tough insulating material attaching each of said plates to the rail engaging portion of a clamp.

In witness whereof, I hereunto set my hand.

JAMES T. ROHM.
